EXTRUDED STRUCTURAL ELEMENT FOR BUILDINGS

Lindell N. Edwards, St. Louis, Mo., assignor to
Universal Modular Structures, Inc., St. Louis, Mo.

Filed Feb. 14, 1972, Ser. No. 226,396

Term of patent 14 years

Int. Cl. D25—01

U.S. Cl. D13—1 H

FIG. 1 is a perspective view of the upper end of an extruded structural element for buildings which embodies my new and ornamental design.

FIG. 2 is a perspective view, displaced one hundred and eighty degrees from the view of FIG. 1, of the upper end of the extruded structural element for buildings shown in FIG. 1, and

FIG. 3 is a sectional view, on an enlarged scale, through the extruded structural element for buildings shown in FIG. 1, and it is taken along the plane indicated by the line 3—3 in FIG. 1.

The extruded structural element for buildings is broken away at the lower end thereof in FIGS. 1 and 2 to indicate indeterminate length.

I claim:

The ornamental design for an extruded structural element for buildings, as shown and described.
